UNITED STATES PATENT OFFICE.

STANLEY H. KNIGHT, OF CHICAGO, ILLINOIS, ASSIGNOR OF ONE-HALF TO CHICAGO HARDWARE FOUNDRY COMPANY, OF NORTH CHICAGO, ILLINOIS, A CORPORATION OF ILLINOIS.

DESIGN FOR A SODA-FOUNTAIN WORK-BOARD.

54,101.

Specification for Design.

Patented Nov. 4, 1919.

Application filed May 14, 1919. Serial No. 297,146. Term of patent 14 years.

To all whom it may concern:

Be it known that I, STANLEY H. KNIGHT, a citizen of the United States of America, residing at Chicago, in the county of Cook and State of Illinois, have invented a new, original, and ornamental Design for Soda-Fountain Work-Boards, of which the following is a specification, reference being had

to accompanying drawing, forming a part thereof, and which represents a perspective view of my new design.

I claim:

The ornamental design for a soda fountain work board, as shown.

STANLEY H. KNIGHT.
